ATTORNEY

UNITED STATES PATENT OFFICE.

SAMUEL FISKE, OF NEW YORK, N. Y.

STEAM-GENERATOR.

SPECIFICATION forming part of Letters Patent No. 326,552, dated September 22, 1885.

Application filed May 25, 1885. (No model.)

To all whom it may concern:

Be it known that I, SAMUEL FISKE, a citizen of the United States of North America, and a resident of the city, county, and State 5 of New York, have invented a new and useful Improvement in Steam-Generators, of which the following is a specification.

This invention relates to steam-generators that are designed more especially for heating 10 buildings.

The objects of the invention are to secure durability, economy in construction and fuel, and convenience in operating; and the invention consists of certain details of construction 15 whereby the largest amount of boiler-surface may be exposed to the heat from the combustion-chamber, whereby the steam may be made dry.

Reference is to be had to the accompanying 20 drawings, forming part of this specification, wherein the letters of reference indicate corresponding parts in all the figures.

Figure 1 is a front elevation of the apparatus. Fig. 2 is a partly-sectional elevation 25 of the same with parts broken away to exhibit other parts. Fig. 3 is a sectional plan on line x , Fig. 2.

In the drawings, A represents the base of the heater, provided with doors A', and supporting the grate B above the ash-pit B'.

The main part of the boiler C, supported on the base A, has a double shell, a a', enclosing an annular water-space, b, which surrounds the combustion-chamber D. The bottom of the water-space b is closed by rings d, to which the lower edges of the said shells are riveted, as shown at d'.

A door, E, in one side of the boiler affords access to the combustion-chamber for feeding 40 fuel thereto.

A large cylindrical water-drum, F, open at the top and having water-connection with the water-space b, and suitably secured to the upper edge of the inner boiler-shell, a, projects centrally down into the combustion-chamber D, thereby making the upper portion 45 of said chamber annular, as indicated in Figs. 2 and 3.

The outer boiler-shell, a', extends above the 50 inner shell, a, and has secured to it by rivets

f a flanged cylindrical drum, G, which forms the top of the boiler and also the steam-chamber thereof, and inserted in the top of the drum G is a steam-exit pipe, g, that is designed to be provided with a suitable valve. 55 The internal diameter of the steam-drum G is preferably the same as that of the water-drum F, and its annular bottom flange, h, extends horizontally outward and is turned down to fit within and against the boiler-shell a', as shown in Fig. 2.

Surrounding the drum G is a flanged shell, H', which is riveted to the horizontal flange of the drum G, as shown at k, and forms an annular space, H, about said drum. 65

A ring of short flues, m, extending upward between the water-space b and the drum F, affords escape for the unabsorbed heat and products of combustion from the combustion-chamber D into the shell H' to dry the steam 70 in the steam-drum G, and finally the products of combustion escape from the steam-drying chamber H through a pipe, o, provided with a valve or damper, o', for regulating the draft. 75

Some of the advantages of a steam-generator of this construction are its cheapness, simplicity, strength, and durability, and that it affords an unusually large combustion-chamber in proportion to its size, and exposes a very 80 large water-heating surface, and also utilizes to great advantage for steam-drying the heat escaping from the combustion-chamber.

I attach importance to the shell H', surrounding the steam-drum and forming an annular space, H, around said drum, for by this construction the steam is dried in the steam-chamber, the heat from the combustion-chamber being utilized for this purpose. 85

I am aware of English patents Nos. 401 of 90 1865 and 1,561 of 1853, and the constructions therein set forth are not sought to be covered in this application.

What I claim as new is—

The combination, with the outer shell, a', 95 and shell H', as shown, of the inner shell, a, arranged in relation to the outer shell to form water-leg b, and having a central depending water-space projecting in the center of the combustion-chamber, the flanged drum C, 100

forming a superheating-chamber, and arranged in relation to the shell H' to form a heating-chamber, which receives the arising products of combustion and surrounds the drum G on all sides and the top, and the short tubes m, connecting the chambers D H, and projecting through the water-space, all arranged and operating as and for the purpose specified.

In testimony that I claim the foregoing as my invention I have signed my name, in presence of two witnesses, this 22d day of April, 1885.

SAMUEL FISKE.
